(57) **CLAIM**

The ornamental design for a tool for lock for liquid dispenser, as shown and described.

DESCRIPTION

FIG. 1 is a front perspective view of a tool for a lock for a liquid dispenser;

FIG. 2 is a front view of the thereof;

FIG. 3 is a back view of the thereof;

FIG. 4 is a left side view of the thereof;

FIG. 5 is a right-side view of the thereof;

FIG. 6 is a top view of the thereof;

FIG. 7 is a bottom view of the thereof; and,

FIG. 8 is another front perspective view thereof, shown in a state of use with environmental subject matter of an exemplary lock and dispenser.

The faded portions shown in FIG. 8 represent environmental subject matter of an exemplary lock and dispenser that form no part of the claimed design.
